MASSAGING AND BATHING APPARATUS

Ellis Kahnt, Chicago, Ill.

Application February 7, 1934, Serial No. 710,047

5 Claims. (Cl. 15—22)

This invention relates to improvements in massaging and bathing apparatus and more particularly to a massaging and bathing apparatus of a unitary construction and has as its principal objects to provide a combined bathing and massaging apparatus of a novel and improved construction wherein a power actuated massaging device is provided in combination with a shower which may be so arranged as to readily be applied to any portion of the body, which device may have water impinged thereon for use for both massaging and cleansing purposes and is arranged with a view towards compactness and utmost efficiency in operation and use of water.

Other objects of my invention will appear from time to time as the following specification proceeds.

My invention may best be understood with reference to the accompanying drawings wherein:

Figure 1 is a side elevation of a device constructed in accordance with my invention with parts broken away and in section to show certain details thereof;

Figure 2 is a top plan view of the device shown in Figure 1 with certain parts removed to more clearly show certain details thereof;

Figure 3 is an enlarged plan view of a portion of the embodiment of my invention shown in Figure 1 with parts broken away and in section to show certain details of my invention;

Figure 4 is an enlarged partial fragmentary sectional view taken substantially along line 4—4 of Figure 3 showing certain details of my invention not shown in Figure 3;

Figure 5 is an enlarged partial fragmentary sectional view taken substantially along line 5—5 of Figure 3 showing certain details of my invention not shown in Figures 3 and 4;

Figure 6 is an enlarged plan view of the massaging device of my invention;

Figure 7 is a longitudinal sectional view taken substantially along line 7—7 of Figure 6;

Figure 8 is a transverse sectional view taken substantially along line 8—8 of Figure 7; and

Figure 9 is a transverse sectional view taken substantially along line 9—9 of Figure 7.

Like reference characters refer to like parts throughout the various figures.

Referring now to the details of construction of the embodiment of my invention illustrated in the drawings, the main elements thereof consist of a base 10 having suitable side walls 11, 11 extending upwardly therefrom a distance sufficient to retain water therein and prevent it from splashing on the floor and permit it to be dis-

charged through a suitable drain (not shown); a power and storage unit 12 carried by said base adjacent one end thereof; a shower nozzle 13; a cleansing and massaging device, generally indicated by reference character 14; a skeleton frame 15 extending vertically upwardly from said base; and fluid repellent curtains 16, 16 carried thereby in the usual manner.

The skeleton frame 15 includes three members 17, herein shown as extending upwardly from the corners of the base 10 and secured thereto in a suitable manner. The members 17, 17 are connected together adjacent their upper ends by means of horizontal connecting members 18, 18. Members 19, 19 are hingedly connected to 15 the upper ends of the members 17, 17 and their outer ends abut each other and are braced by means of detachable braces 19a, 19a. The members 18, 19 may be connected together at their ends and said members with the members 18, 18 20 are so arranged that their outline in plan is substantially a rectangle. The members 18, 18 and 19, 19 serve as a support for rings 20, 20 which carry the shower curtain 16, 16 thereon. Suitable arcuately formed rods 21, 21 are provided adjacent the lower ends of the shower curtains 16, 16 beneath the top of the side walls 11, 11 for slidably supporting the lower ends of the curtains 16, 16.

With reference now in particular to the details 30 of the power and storage unit 12 and several of the novel features of my invention, said unit is enclosed by means of side walls 23 and 24 extending upwardly from the base 10 and abutting the side walls 11, 11, and a cover 25 enclosing the top 35 thereof. The side wall 23 is lower than the side wall 11 so the cover 25 may be inclined to permit water to drain therefrom. The joints between the cover and side walls 11, 11, 23 and 24 may be of a suitable water-tight construction to prevent water from entering the enclosure for the power unit.

A fluid storage tank 27 is provided within the enclosure formed by the side walls 11, 11, 23 and 24 and is of an ordinary construction being provided with an opening closed by a cover 28, a pressure outlet including a pipe 29 and a by-pass opening 30. As herein shown, the storage tank 27 may be filled with water of the desired temperature through the opening, closed by the cover 26, although it is obvious that if desired the device may be so arranged that either heated or cold water taken from the ordinary household hydrant may be discharged into said storage tank, and that suitable heating and temperature 55

control apparatus may be provided for said tank, said apparatus not herein being shown since it is no portion of my present invention.

The pipe 29 is connected to and serves as an inlet to a pressure pump indicated by reference character 31. The pump 31 may be of any suitable construction, but is herein preferably shown as being a gear pump of a usual construction, so arranged as to take up a small amount of vertical and lateral space and still be of sufficient capacity to effect the required pressure to the system. A pipe line 33 is connected to the pressure side of the pump 31 and extends upwardly therefrom. The pipe line 33 is braced to the members 17, 17 in a suitable manner, as is clearly shown in Figure 1, and forms a fluid conductor for the shower nozzle 13 which nozzle is mounted in a ball and socket 34 so it may be directed where desired. A valve 35 is provided in the pipe line 33 to control the flow of water through the nozzle 13. A T 36 is connected in the pipe line 33 and has a flexible tube 37 connected thereto in a suitable manner, which tube leads to the massaging device 14 for directing water thereon under control of the operator in a manner which will hereinafter be more fully described.

A by-pass line 38 leads from the pipe line 33 to a by-pass valve 39 connected to the by-pass opening 30 in the storage tank 27. The by-pass valve 39 is of the ordinary spring controlled ball type for by-passing water to the storage tank 37 when the valves to the shower and massaging device are not in use and when pressures in the system become excessive.

The pump 31 is mounted on a base 40 spaced above the bottom 10 of the enclosure for the power and storage unit 12 and extending from the storage tank 27 to the end thereof. A motor 41 is mounted on the base 40 adjacent an end thereof opposite the tank 27 and is insulated therefrom by means of suitable insulating members indicated by reference character 43. (See Figure 4.) The motor 41 may be of any type well known to those skilled in the art, but is herein preferably shown as being an enclosed electric motor of a water tight construction. The motor 41 may be controlled in any suitable manner; as, for instance, a push button control remote from the motor and mechanism (not shown), so that it must be turned on before the bather enters the apparatus and can turn on the water, in order to minimize the danger of electrical shocks.

The motor 41 is provided with a shaft 44 which has driving connection with an alined shaft 45 by means of a coupling member 46. The shaft 45 is journaled in a gear housing 47 secured to the base 40. A pinion 48 is keyed on the shaft 45 and meshes with and drives a spur gear 49 keyed on a shaft 50. The shaft 50 is journaled in the gear housing 47 and has an eccentric 51 formed integral therewith adjacent the spur gear 46 and is operatively connected with the pump 31 in a suitable manner for driving said pump.

An eccentric strap 53 is journaled on the eccentric 51 and has a connecting member 54 formed integral therewith pivotally connected with a push rod 55 by means of a pivotal pin 56. The push rod 55 is guided within an upstanding projection 57 from the gear housing 47, which projection extends through the cover 25. Suitable packing may be provided between the projection 57 and the cover 25 as well as between the pipe line 33 and said cover to keep water from passing through said cover.

With reference now in particular to the details

of the massaging device 14 and several other of the novel features of my invention, a flexible drive shaft 59 is secured to the upper end of the push rod 55 and held thereto by means of a nut 60. The opposite end of the flexible drive shaft 59 has an annular formation 61 thereon having a convex face which is carried within a ball shaped socket 62 formed in the end of a rod 63 for pivotal movement with respect to said rod. The rod 63 is carried in a member 64 for slidable movement with respect thereto. The member 64 in turn is carried within a handle 65 of the massaging device 14 and held from movement with respect thereto by means of a set screw 66.

A flexible housing 67 is spaced from and surrounds the flexible drive shaft 59 and is secured to the projection 57 adjacent one of its ends by means of a member 68 threaded on said projection. The opposite end of the flexible housing 67 is secured to the member 64 in a suitable manner by means of a member 69 threaded on the rearward end of said member.

A body portion 70 is herein shown as being formed integral with handle 65 and is provided with a pair of inwardly facing parallel-spaced longitudinally extending guides 71, 71 formed therein and adapted to form a slidable support for a plate 73. The plate 73 has an integral bifurcated connecting portion 74 extending rearwardly therefrom connected to the rod 63 by means of a pin 75.

A brush 76 is adapted to be detachably secured to the plate 73 by means of a clip and ball connection, generally indicated by reference character 71. The arrangement is such that the type 35 of brush used may be readily changed, or a sponge rubber or analagous massaging device may be substituted therefor if desired.

It is thus apparent that rotation of the motor 41 will reciprocably move the brush 76 at a relatively high rate of speed through the eccentric 51 and flexible shaft 59 and that said brush may be so reciprocated when in various positions on the body, said flexible shaft being of sufficient length to permit said brush to reach any portion on the 45 body. It should be noted that while I have herein shown the brush 76 as being reciprocably driven by means of a motor and eccentric that it may be reciprocated by water pressure or various other means without departing from the spirit and scope of my invention.

With reference now to the means for controlling the flow of water from the flexible tube 37 to the bristles of the brush 76 said tube is held to the flexible housing 67 in a suitable manner 55 for movement therewith and secured to the end of a connecting member 79 threaded within the handle 65, which member leads to a chamber 80. The chamber 80 leads to a passageway 81 in the handle 65 and may be closed by means of a valve 83, which valve is normally held in a closed position by means of a spring 84 encircling an extension 85 of the stem of said valve and interposed between a collar 86 and said handle. The valve 83 and chamber 80 may be opened to admit 65 fluid under pressure into the passageway 81 by means of an operating lever 87 having a forked portion 88 pivotally secured to opposite sides of the handle 65 and having a recessed portion 89 adapted to engage the end of the extension 85 70 of the stem of the valve 83 so that movement of said operating handle in one direction will compress the spring 84 and open said valve.

A pair of pipes 90, 90 lead forwardly from the passageway 81 and upwardly therefrom and along 75

opposite sides of the body portion 10 and are secured to flanges 91, 91 formed integral with said body portion and disposed adjacent opposite sides of the brush 16. The ends of the pipes 90, 90 are closed and a plurality of openings 92, 92 directed towards the brush 16 are provided therein so that water under pressure may be directed to said brush.

It is thus apparent that when using the massaging device 14 for massaging purposes it is not necessary to apply water thereto, but that water under pressure may be applied to said massaging device when desired by squeezing the operating lever 87. It may also be seen that since the flow of water is under the control of the bather and is normally shut off, that a considerable saving in water may be effected in normal bathing operations, the shower nozzle 13 only being in use when it is desired to completely rinse off.

It may now be seen that I have provided a new and useful bathing apparatus of a novel, compact, efficient and unitary construction which may readily be moved from place to place and is particularly adapted for use in places having a limited water supply and where water is not supplied under pressure.

It may also be seen that the device of my invention may be used for massaging as well as bathing purposes and that where conditions are such that water is supplied under pressure, the tank 27 and pump 31 may be eliminated and the water connections may be made direct from the ordinary plumbing connections.

While I have herein shown and described one form of my invention, it will be understood that the construction and arrangement of the various parts may be altered without departing from the spirit and scope thereof. Furthermore, I do not wish to be construed as limiting myself to the specific form illustrated, excepting as it may be specifically limited in the appended claims.

I claim as my invention:

1. A massaging apparatus including a handle, a massaging member supported thereby for reciprocable movement with respect thereto, and means for reciprocably moving said massaging member with respect to said handle comprising a frame remote from said massaging member, a motor, a reciprocably movable member driven by said motor and supported in said frame, and a flexible drive connection between said reciprocably movable member and massaging member comprising a flexible housing connected between said handle and frame and a flexible drive shaft carried within said housing and operatively connected between said reciprocably movable member and massaging member.

2. In an apparatus of the class described, a frame having a reciprocably driven member guided for movement therein, a massaging device, flexible drive means for operating said massaging device including a flexible housing secured to said frame at one of its ends and a flexible drive shaft carried therein and secured at one of its ends to an end of said reciprocably driven member, said massaging device including a body portion having a handle extending rearwardly therefrom, said body portion having parallel spaced guides on one side thereof having a support plate slidably mounted therein, said plate having a massaging member secured to the upper face thereof and having a portion extending rearwardly therefrom within said handle, and a drive connection from said flexible drive shaft to said plate for reciprocably moving said plate in said

guides including a member guided for reciprocable movement in said handle and having operative connection with said portion of said plate extending within said handle at one of its ends, a connection between the free end of the housing and the rearward end of said handle, and an operative connection between the free end of said flexible drive shaft and said member guided in said handle.

3. In an apparatus of the class described, a frame having a reciprocably driven member guided for movement therein, a massaging device, flexible drive means for operating said massaging device including a flexible housing secured to said frame at one of its ends and a flexible drive shaft carried therein and secured at one of its ends to an end of said reciprocably driven member, said massaging device including a body portion having a handle extending rearwardly therefrom, said body portion having parallel spaced guides on one side thereof having a support plate slidably mounted therein, said plate having a massaging member secured to the upper face thereof and having a portion extending rearwardly therefrom within said handle, and a drive connection from said flexible drive shaft to said plate for reciprocably moving said plate in said guides including a member guided for reciprocable movement in said handle and having operative connection with said portion of said plate extending within said handle at one of its ends, a connection between the free end of the housing and the rearward end of said handle, and an operative connection between the free end of said flexible drive shaft and said member guided in said handle comprising a substantially ball-shaped socket on the end of said member and an annular formation on the end of said flexible drive shaft having a convex outer periphery adapted to engage said socket.

4. In a massaging apparatus, a massaging device comprising a member having a brush reciprocably movable with respect thereto, a handle extending from said member, a flexible housing interposed between said handle and a frame remote therefrom, and a reciprocably driven flexible drive shaft carried within said housing, said drive shaft being connected with a reciprocably driven member guided within said frame at one of its ends and with a member slidably guided within said handle at its other end, and said last-named member having operative connection with said brush for reciprocably driving said brush, said handle having a fluid passageway leading to opposite sides of said brush for applying fluid to said brush independently of reciprocable movement thereof, and an operating lever pivoted to said handle for controlling the passage of fluid to said brush, whereby said lever may be manually operated by the hand which holds said handle while applying said massaging device to the body.

5. In an apparatus of the class described, a massaging device including a support member having a massaging member guided for reciprocable movement with respect thereto, a handle extending from said support member, a flexible drive shaft having connection with said massaging member adjacent one of its ends and a reciprocably driven member adjacent its opposite end, and a flexible housing enclosing said drive shaft and connected between said handle and a member fixed from reciprocable movement with respect to said reciprocably driven member, said handle having a fluid passageway therein, means for con-

ducting fluid to said passageway including a valve in said handle for admitting fluid under pressure thereto, means communicating with said passageway and extending along opposite sides of said 5 massaging member for conducting fluid to said massaging member independently of reciprocable

movement thereof, and an operating lever on said handle for controlling said valve so arranged that said lever may be manually operated by the hand which holds said handle while applying said massaging device to the body.

ELLIS KAHNT. 5
